US00D956122S

(12) **United States Design Patent** (10) **Patent No.:** **US D956,122 S**
Zhong (45) **Date of Patent:** **** Jun. 28, 2022**

(54) **LENS**

(71) Applicant: **Shaohua Zhong**, Guangdong (CN)

(72) Inventor: **Shaohua Zhong**, Guangdong (CN)

(**) Term: **15 Years**

(21) Appl. No.: **29/801,601**

(22) Filed: **Jul. 29, 2021**

(30) **Foreign Application Priority Data**

Jun. 8, 2021 (CN) 202130352130.2

(51) **LOC (13) Cl.** **16-01**

(52) **U.S. Cl.**

USPC **D16/219**

(58) **Field of Classification Search**

USPC D16/200–204, 205–211, 212–215,

D16/218–219, 237, 242, 244

CPC .. G03B 17/02; G03B 17/56; G03B 2217/243;

H04N 5/2251; H04N 5/2254

See application file for complete search history.

(57) **CLAIM**

The ornamental design for a lens, as shown and described.

DESCRIPTION

FIG. 1 is a perspective view of a lens showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the lens that form no part of the claimed design.

1 Claim, 4 Drawing Sheets
